CLAIM

The ornamental design for a shoe sole, as shown and described.

DESCRIPTION

FIG.1 is a photographic perspective view of a shoe sole showing my new design;

FIG. 2 is a photographic right side view thereof;

FIG. 3 is a photographic left side view thereof;

FIG. 4 is a photographic front view thereof;

FIG. 5 is a photographic rear view thereof;

FIG. 6 is a photographic bottom view thereof;

FIG. 7 is a photographic top view thereof;

FIG. 8 is a photographic perspective view of another embodiment thereof;

FIG. 9 is a photographic right side view thereof;

FIG. 10 is a photographic left side view thereof;

FIG. 11 is a photographic front view thereof;

FIG. 12 is a photographic rear view thereof;

FIG. 13 is a photographic top view thereof; and,

FIG. 14 is a photographic bottom view thereof.

The claimed design is indicated by the relatively dark portions in the figures. The relatively light portions form no part of the claimed design.

1 Claim, 14 Drawing Sheets(56)
